UNITED STATES PATENT OFFICE.

ELMER R. CORWIN, OF CHICAGO, ILLINOIS, ASSIGNOR TO CORWIN TELEPHONE MANUFACTURING COMPANY, OF CHICAGO, ILLINOIS, A CORPORATION OF ILLINOIS.

TELEPHONE SYSTEM.

1,085,974.

Specification of Letters Patent.

Patented Feb. 3, 1914.

Application filed October 12, 1908, Serial No. 457,196. Renewed May 28, 1913. Serial No. 770,491.

To all whom it may concern:

Be it known that I, ELMER R. CORWIN, citizen of the United States, residing at Chicago, in the county of Cook and State of Illinois, have invented a certain new and useful Improvement in Telephone Systems, of which the following is a full, clear, concise, and exact description, reference being had to the accompanying drawings, forming 10 a part of this specification.

My invention relates to telephone exchange systems and has for a broad object the provision of means whereby telephonically connected stations of calling and called 15 lines may, independently of each other, resume control of their connection initiating line equipment at the exchange or exchanges to which these lines extend to enable either station to initiate a new connection while 20 engagement is still maintained between contacts of its line and of the link connector which is employed to connect the lines.

When the invention is embodied in a manual switch board system it affords 25 means whereby a subscriber after restoring his receiver upon finishing conversation, is in control of his line indicator irrespective of the condition of use of the cord connecting apparatus, whereby the operator in attending upon his call, will respond thereto, rather than the operator who took part in establishing the existing connection. As a concrete example, let it be assumed that a subscriber after having been called and having finished conversation with the subscriber calling him, desires to become a calling subscriber. In order to do so, the said called subscriber who has become the calling subscriber, restores his receiver to his switchhook, whereby through the means of my invention, such called subscriber is thrown out of further control of his supervisory signal forming a part of the connection that said called subscriber previously had, and where- 30 by said called subscriber is placed in control of his line signaling apparatus which then no longer remains under the control of the cord circuit employed in establishing the previously existing connection. In this way 50 a subscriber who is through with a connection, is enabled at once to signal the operator who has been assigned to attend to his incoming calls, such operator being in a position to serve his wants rather than the

operator (assuming her to be situated at 55 another position of the switch-board) who had presided over or took part in establishing the original connection.

By means of my invention, the operators that have been selected according to their 60 capacity to attend to the traffic of the exchange, do not attend to any incoming calls except those that initiate in line signals, it being understood that with the system of my invention neighboring operators may assist 65 each other in responding to line signals, as is at present the practice.

My invention has also for its object the provision of mechanism for automatically controlling the association of the operator's 70 telephonic apparatus and the ringing generator with cord circuits and the provision of an improved testing circuit arrangement.

The various features and advantages of my invention will more fully appear by a 75 description of the preferred embodiment thereof, shown in the accompanying drawing, that illustrates one type of a multiple switch-board telephone exchange system to which my invention may be adapted, but to 80 which type of multiple switch-board system I do not wish to be limited.

I have shown at A B two telephone sub-stations each including a receiver *a*, a transmitter *b*, a switch-hook *c*, a call bell *e*, and a condenser *f*, the elements *a b c* being included in bridge of the telephone line, which bridge is open when the receiver is upon the switch-hook *c* and which bridge is closed by the switch-hook when relieved of 90 the weight of the receiver. The elements *e f* are included in another bridge permanently continuous with respect to alternating signaling currents but non-continuous with respect to direct currents. The type of 95 sub-station outfit shown is one that I have selected for the purpose of illustrating the invention, but it is to be understood that I do not limit myself to the form of sub-station apparatus shown, for it will be obvious as the description of the invention is proceeded with, that the operation of the system does not depend upon the peculiar sub-station outfit shown. The stations A B are connected to the exchange, in the form 100 of the invention shown, by means of metallic circuits whose limbs *g* and *h* are connected with line springs or talking contacts

of spring jacks g^1 h^1 . A plurality of spring jacks is shown in multiple relation with each line, the lowermost spring jacks constituting the answering jacks while the remaining jacks constitute line jacks. The limbs h of each telephone line also terminate in a contact of an armature switch, which switch is governed in its position by the cut-off relay or magnet i , the limbs of each telephone line being normally connected by way of said armature switch and the contact normally engaged thereby, with a line lamp or signal k and a battery k^1 adapted to excite said lamp when the circuit including the battery k^1 , the line signal k , the armature switch of the associate cut-off relay i and the line limbs g and h , is closed by the removal of the telephone receiver at a calling station from its supporting switch-hook. The limbs g and h of each telephone line are shown as being grounded, taps for the purpose being continued from the limbs after their connections with the jacks have been passed, which taps are grounded and which include the elements k k^1 named. In order to prevent the leakage of voice currents, the grounded tap of each line in permanent connection with the battery k^1 (the battery k^1 may be common to a group of lines, as is well understood) has a retardation coil k^2 included therein. The cord circuit illustrated includes an answering plug l and a connecting plug l^1 whose tips and sleeves are united by tip and sleeve talking strands and whose body portions l^2 are adapted for engagement with the thimbles of the answering and line multiple jacks.

Assuming that a subscriber, say subscriber A, has initiated a call by removing his telephone receiver from its switch-hook, and thereby closing the circuit through the line signal device k , the operator in response to the signal conveyed by the device k will insert the answering plug l into the jack (in this case the answering jack h^1) corresponding to the calling subscriber, whereupon circuit is established through the calling subscriber's cut-off relay or magnet i (thereby to cut out the signal device by the operation of the cut-off relay i), which said circuit may be traced from the grounded terminal of said cut-off relay, through the thimble of the answering jack h^1 , the body portion l^2 of the answering plug, the left-hand armature switch of the relay m (which relay is brought into service in order to place the calling subscriber in control of his line signal after said subscriber has finished with a connection, all as will herein-after be set forth), the armature switch and normal contact of the relay n (which relay is employed to convey to the subscriber a busy test signal, as will appear), the lower winding of the differential relay o , to the

battery p . Upon this inclusion of one winding of the differential relay o in circuit, the three armature switches shown in association with this differential relay are attracted, the two upper armature switches o^1 70 bridging the operator's telephone outfit o^2 across the talking strands of the cord circuit, the lower armature switch o^3 connecting the battery p as a talking battery in a local circuit including the operator's transmitter o^4 . During this stage of the operation of the system, the calling subscriber's supervisory relay q is energized, owing to the closure of the circuit therefor at the calling subscriber's switch-hook, the circuit 80 for this supervisory relay remaining closed until the calling subscriber has restored his receiver to its switch-hook, the calling subscriber's supervisory signal display device q^1 remaining on open circuit during the energization of the associate supervisory relay q owing to the separated relation of the contacts of the lowermost armature switch of said supervisory relay. The circuit for the supervisory relay, established by the 90 closure of the calling subscriber's switch-hook, may be traced from the grounded battery k^1 , the limbs and sub-station outfit of the calling subscriber's line, the sleeve line spring of the jack engaged by the answering plug, the sleeve contact of the answering plug, the supervisory relay q , to the grounded armature switch of the relay m by way of its normal contact. The operator's telephone outfit o^2 having been connected in bridge of the cord circuit by the inclusion in circuit of the lowermost winding of the differential relay o in the manner that has been specified, the operator is 95 in position to learn of the wants of the calling subscriber. Ascertaining, for example, that the calling subscriber desires connection with subscriber B, the operator takes the testing plug, which may be the connecting plug l^1 that is the mate of the answering plug l , and touches its tip to the testing thimble of a line jack of the called subscriber. If the line happens to be busy, grounded battery p will be connected with the thimbles of all of the jacks of the called line by way of the connections illustrated, 100 including the body l^2 of a plug inserted into one of said jacks. If the called line is idle, the thimbles of the jacks thereof are not connected with the battery p . If battery 110 p is connected with the thimble of a tested jack, the test circuit established may be traced from the grounded battery p to the thimble of the tested jack, the applied tip of the testing plug, the uppermost armature switch of the relay r , together with its normal contact (the function of the relay being explained later), the winding of the test relay s , to its grounded armature switch by way of its normal contact, such circuit 120 oc- 130

casioning the vibration of the relay s to indicate to the operator that the line tested is busy. I also desirably provide the operator with a visual test signal s^1 that may be common to the cords at her position, and circuit through which may be traced from the grounded battery p to the left-hand armature switch of relay s , to the grounded signal lamp s^1 by way of the front contact 5 of said armature switch. In order that the calling subscriber may be satisfied that the party desired is already in use of his telephone line, I provide a busy back system, which includes, in the embodiment of the 10 invention shown, a local circuit s^2 that includes a primary coil s^3 upon which intermittent or alternating current is suitably impressed, the secondary coil s^4 terminating in the contacts of the upper armature 15 switches of the relay n . The relay n is energized each time the test relay s is energized, through a circuit which may be traced from the grounded armature switch of the relay s , the alternate contact of said switch, 20 the lower armature switch of relay r and its contact, the winding of relay n , to the grounded battery p . Each time the relay n is energized, the secondary s^4 is connected across the talking strands of the cord circuit, 25 so that the receiver of the calling subscriber is operated to indicate that the wanted line is busy. Assuming that there is no battery maintained upon the thimbles of the jacks of a called line (which is the 30 case when the called line is idle), the relay s will occasion or cause no signal, whereupon the operator will insert the answering plug into the tested jack. Upon the insertion of 35 the connecting plug, the operator's telephone set is immediately cut out of circuit and the talking battery p is removed from her transmitter o^4 by reason of the circuit established through the upper coil of the differential magnet o , which counteracts the magnetization 40 of the lower coil, allowing the armature switches o^1 o^3 of the relay to fall back. The circuit that is established for the purpose of cutting out the operator's telephone outfit may be traced from the grounded cut-off 45 relay i of the called line, the thimble of the line jack of the called line engaged by the connecting plug, the body l^2 of such plug engaging said thimble, the armature switch of relay n , together with its normal contact, 50 the upper winding of the differential relay o , to the grounded battery p . Circuit is also closed through the relay r whose upper armature switches are attracted to close the openings in the talking strands thereat 55 and whose lower armature switch is attracted to prevent operation of the relay n . 60

Before describing the manner in which the ringing current is impressed upon the called subscriber's line, I will slightly describe the ringing outfit illustrated, which

includes a motor generator v , the motor side of which is in closed circuit with the battery p and the generator side of which impresses ringing current upon the slip ring terminals v^1 , which are borne upon by 70 brushes that are connected with the normal contacts of the two upper armature switches of the relay w , said armature switches when in their normal unattracted positions, permitting calling current to be impressed 75 upon the talking strands, such calling current being conveyed to the line when the relay r is energized, to have its upper armature switches close the breaks in the talking strands, as has been described. In 80 order that the signal device or bell e at the called station may be rung intermittently, I periodically interrupt the ringing current impressed upon the upper armature switches of the relay w by means of the 85 upper armature switches of the relay t^1 , which, together with their normal contacts, are in serial relation with the upper armature switches of the relay w . The relay t^1 is for the purpose intermittently energized 90 through a circuit which may be traced from the grounded battery p to the brushes x , which bear upon a rotating collar x^1 made of segments of metal and insulating material for the purpose of alternately electrically 95 connecting said brushes and electrically separating said brushes, thence to the lower coil of the relay t^1 , the lower armature switch of relay w , which is to be energized, the armature switch of relay u and its normal contact, the body l^2 of the connecting plug, to the grounded cut-off relay i of the 100 called subscriber's line. As the composite collar x^1 rotates, the lower winding of the relay t^1 is alternately energized and de- 105 energized, whereby the armature switches of said relay t^1 are intermittently operated to intermittently open and close the conductors that convey signaling current from the calling generator terminals v^1 to the 110 connecting end of the cord circuit which conveys signaling current to the bell at the called subscriber's station over the called subscriber's line. Prior to the response of the called subscriber, his clearing-out signal device or lamp t is included in a circuit which may be traced from the grounded battery p , through said lamp, to the lower armature switch of the relay t^1 , the armature 115 switch of relay u and its normal contact, the body l^2 of the connecting plug, to the called subscriber's cut-off relay i . When the called subscriber responds, the upper coil of the magnet w is included in a circuit which may be traced from the grounded terminal 120 of said coil, through the upper coil of the relay t^1 , the armature switch of said relay t^1 (shown next the core thereof), the called subscriber's portion of the sleeve talking strand of the cord circuit, the engaged sleeve 125

130

line spring of the called subscriber's jack, the limb h of the called line, the telephone bridge at the called subscriber's station, to the grounded battery k^1 . The relay w is thereupon energized to move its upper armature switches away from their normal or generator contacts, whereby the generator is automatically removed from circuit with the called subscriber's line, the lowermost armature switch of said relay w being also attracted to open the interrupter circuit that includes the lowermost coil of the relay t^1 , whereby the armature switches of said relay t^1 are no longer vibrated, the upper winding of the relay t^1 being in the circuit that was traced through the upper winding of the relay w , whose armature switch is attracted, whereby the openings in the cord circuit strands at the upper armature switches are closed, the circuit of the called subscriber's supervisory signal t being at the same time opened at the lowermost armature switch of the relay t^1 , which thus performs the functions of a supervisory relay.

When the lowermost switch of the relay w is attracted, it moves against an alternate contact that constitutes the terminal of the lower winding of said relay, which is thereupon included in a local circuit that is maintained as long as the connecting plug is inserted within the called subscriber's jack, and which local circuit may be traced from the grounded battery p , to the lowermost winding of the relay w , thence to the lowermost armature switch, the armature switch of relay u , the normal contact of relay u , the body l^2 and the grounded thimble of the called subscriber's jack, it being understood that the resistance of the cut-off relays i are low as compared with the resistance of the upper winding of relay o ; for example, the resistance of the relays i being ten ohms and that of the said winding of relay o being five hundred ohms. A locking circuit is thus established for the relay w that will prevent the re-application of signaling current to the line when the called subscriber restores his telephone and which will prevent the energization of the relay t^1 , owing to the opening of the circuit of the lower coil of the relay t^1 at the lowermost armature switch of the relay w . When the subscribers have finished conversation, they restore their telephones to their switch-hooks, and inasmuch as I have just been describing the operation of the called subscriber's apparatus, I will describe in detail the operation of the called subscriber's supervisory signal that then ensues and the operation of the associate apparatus.

As has been explained, the energization of the upper winding of the relay t^1 depends upon the circuit that has been traced from the grounded terminal of the upper winding 65 of the relay w , through the upper winding

of the relay t^1 , through the limb h of the called line, to grounded battery k^1 . This circuit is broken when the called subscriber restores his telephone, inasmuch as the condenser f does not afford a continuous path for the current from the battery k^1 . The circuit through the upper winding of the relay t^1 is therefore opened when the called subscriber restores his receiver, and the circuit through the lower winding of the relay t^1 being maintained open by the attraction of the lowermost armature switch of the relay w , the armature of the relay t^1 is allowed to fall back, the circuit through the supervisory lamp t being thereby closed at the lowermost armature switch of the relay t^1 . Upon the deenergization of the relay t^1 , circuit is established through the relay u , which may be traced from the grounded coil of said relay, the alternate contact of the uppermost switch of the relay w now engaged by said switch, the normal contact of the uppermost switch of relay t^1 now engaged by said switch, the alternate contact of the uppermost switch of relay r , to the tip of the connecting plug, thence to the grounded battery k^1 . The relay u , upon its energization, removes the ground from the armature switch of said relay connected therewith by way of the normal contact of said relay, the body of the calling plug and the cut-off relay of the called subscriber, ground, however, being reestablished in connection with the armature switch of said relay upon the attraction of said armature switch, whereby the lower coil of the relay w is still maintained in circuit, as must be apparent in view of the fact that the new ground upon the armature switch of relay u performs the functions of the ground previously placed upon said armature switch, by way of the body of the connecting plug. The circuit of the cut-off relay i of the called subscriber is therefore opened at the normal contact of the armature switch of relay u , so that said called subscriber after having once restored his receiver, is placed in full control of his line lamp h , so that he may signal his own operator, in order that he may at all times be assured of her service. In this way if the called subscriber desires to be connected with another subscriber immediately after having concluded his previous conversation, he may place himself in direct relation with his own operator, to the end that she may attend to his wants. When the operator withdraws the calling or connecting plug in response to the signal revealed at t , she opens the circuit for the relay u by separating the tip of the connecting plug l^1 from the spring engaged thereby, whereupon ground is removed from the clearing-out or supervisory signal t that is thus restored to normal. The ground that was employed to lock the relay w is also 130

removed, so that the switches of said relay are released, as are also the switches of the relay r . Ground is also removed from the upper winding of the relay o , so that if the 5 calling subscriber has not restored, the lowermost winding of the relay o is alone included in circuit, thereby again to connect the operator's set with the cord circuit, so that the operator may converse with the 10 calling subscriber with whom she initially established connection. Inasmuch as the operator does not withdraw the plugs uniting lines in conversation until both supervisory signals $q^1 t$ are presented, both windings of the neutral or differential relay o are energized, so that when the calling subscriber's supervisory relay q is deenergized upon the re-location of the calling subscriber's receiver upon its switch-hook, the 15 relay m is energized through a circuit which may be traced from the grounded battery k^1 to the tip of the answering plug l , the normal contact of the uppermost switch of the supervisory relay q , the winding of the relay m , the adjacent lower armature switch of the said supervisory relay q and its normal contact, to ground by way of the armature switch o^3 and its normal contact. When the armature switches of the supervisory 20 relay q are released (which, as has been stated, is due to the opening of the circuit therefor at the calling subscriber's station), circuit is established for the calling subscriber's supervisory signal q^1 , which may be 25 traced from the grounded battery p , through the supervisory signal device q^1 , the lowermost armature switch of the relay q and its contact, thence to the left-hand armature switch of the relay m , to the grounded alter- 30 nate contact of said armature switch. By the movement of the left-hand armature switch of the relay m , which is occasioned by the energization of the relay m , ground is removed from the calling subscriber's cut- 35 off relay i , so that the calling subscriber's line signal h is again placed within the control of said subscriber, whereby the subscriber does not have to wait until the answering plug is withdrawn from his an- 40 swering jack before he can secure the operation of his line indicator. In this way the calling subscriber is sure of getting the services of his own operator, and does not run the chance of securing the services of 45 an operator at distant sections of the board. When the connection is taken down, the circuit through the magnet m is opened by the disengagement of the tip of the plug l from the tip line spring of the answering jack h^1 , 50 so that said relay m is deenergized and the supervisory indicator q^1 is restored to normal, as is the case with the other associate parts of the cord circuit apparatus.

Having described the general features of 55 my invention, I will now describe some de-

tails, a description of which having hitherto been omitted for the sake of clearness.

It will be understood that when the relays m and u are energized, they remove the testing battery p from connection with the thimbles of the jacks, so that when said lines are tested they will test free, though the plugs l , l^1 may still be within the jacks. It goes without saying that the batteries p h^1 may be merged into a single battery, and 70 take part not only in supplying the operator's telephone outfit with straight current, but also may be employed to supply the connected transmitters of subscribers' stations with straight current. If the called subscriber 75 has not restored his telephone, the operator may be thrown into communication with him upon the removal of the plug l , owing to the energization of but one coil, the upper coil, of the relay o .

Referring back to the operation of the composite collar x^1 , I would point out that it serves the important function of causing an intermittent operation of the called subscriber's supervisory signal t during the 80 time that the ringing current is being impressed upon the called subscriber's line, whereby the operator may readily determine whether or not the called subscriber is still being called or whether, having been called, 85 he has finished with the connection, for in the latter case the signal device t would preserve but one set display condition. A third function of the supervisory signal device is, of course, to indicate to the operator 90 that the called subscriber has responded.

Attention should be particularly directed to another feature of my invention which, in one embodiment, resides in the apparatus illustrated, whereby after a subscriber 105 has restored his telephone to its switch-hook, his supervisory signal is as a consequence removed from his control, so that it assumes a set display condition.

It will be seen that I have provided a telephone system including telephone lines extending to an exchange from sub-stations, jack switches in association with the telephone lines, connecting plugs for engagement with said switches, a source of signaling current for operating the signal receivers at called sub-stations and in normal connection with a section of the plug circuit, which said section is normally disconnected from the answering and connecting ends of the plug circuit, and relay mechanism serving to control the connection of said section of the plug circuit with the answering and connecting ends of said plug circuit and to remove the calling generator from its normal association with said section of the plug circuit.

Cross reference is made to my co-pending application Serial No. 639,203, filed July 18, 1911, originally filed October 12, 1908 under 130

Serial No. 457,197 and in which some features that are herein disclosed are therein disclosed.

I have herein shown and particularly described the preferred embodiment of my invention, in order that the invention in all of its aspects may be well understood. I do not wish to be limited, however, to the form of the invention that has been selected to illustrate it; as changes may readily be made without departing from the spirit of the invention.

It will be seen that I have provided a telephone exchange system including telephone lines extending from sub-stations to an exchange, line signaling apparatus at the exchange for said telephone lines, connecting apparatus at the exchange for uniting lines in conversation, a cut-off relay governed by said connecting apparatus for preventing the presentation of the line signal of a called line or a calling line, as the case may be, and electro-magnetic mechanism operable by the apparatus at the called station or calling station, as the case may be, independently of the apparatus of the calling station or called station, as the case may be, for removing the control of the cut-off relay from the line signal of the called line or calling line, as the case may be, thereby permitting the called station or calling station, as the case may be, to have control of the line signal of the called line or calling line, as the case may be.

Having thus described my invention, I claim as new and desire to secure by Letters Patent the following:

1. A telephone exchange system including telephone lines extending from sub-stations to an exchange, line signaling apparatus at the exchange for said telephone lines, connecting apparatus at the exchange for uniting lines in conversation, means governed by said connecting apparatus for effacing the line signal of a calling line, and means operating independently of the apparatus at the called station and jointly controlled by the connecting apparatus, when it is employed in establishing a connection, and the sub-station apparatus of the calling line for restoring to the sub-station of the calling line its control of its associate line signal apparatus during an established connection.

2. A telephone exchange system including telephone lines extending from sub-stations to an exchange, line signaling apparatus at the exchange for said telephone lines, connecting apparatus at the exchange for uniting lines in conversation, means governed by said connecting apparatus for preventing the presentation of the line signal of a called line, and means operating independently of the apparatus at the calling station and jointly controlled by the connecting apparatus, when it is employed in establishing

ing a connection, and the sub-station apparatus of the called line for restoring to the sub-station of the called line its control of its associate line signal apparatus during an established connection.

3. A multiple switch-board system having a test system which includes test thimbles or contacts of jacks, testing terminals of plugs applied to said jack contacts before the plugs are plugged into the jacks, a test circuit including jack test contacts, contacts of plugs plugged into said jacks and engaging the test contacts thereof, the testing terminal of an applied testing plug and a suitable source of testing current, means whereby a completed test circuit is caused to convey a busy signal to a calling sub-station, said means including a relay for connecting test busy current in association with a calling telephone line, and a relay in the test circuit for effecting the operation of the aforesaid relay.

4. A multiple switch-board system having a test system which includes test thimbles or contacts of jacks, testing terminals of plugs applied to said jack contacts before the plugs are plugged into the jacks, a test circuit including jack test contacts, contacts of plugs plugged into said jacks and engaging the test contacts thereof, the testing terminal of an applied testing plug and a suitable source of testing current, means whereby a completed test circuit is caused to convey a busy signal to a calling sub-station, said means including a relay for connecting test busy current in association with a calling telephone line, a relay in the test circuit for effecting the operation of the aforesaid relay, and means under the control of the calling line station for dissociating the busy test system from the calling line.

5. A telephone exchange system including telephone lines extending from sub-stations to an exchange, line signaling apparatus at the exchange for said telephone lines, connecting apparatus at the exchange for uniting lines in conversation, a cut-off relay governed by said connecting apparatus, for preventing the presentation of the line signal of a called line, and means, operable by the called party independently of the apparatus of the calling station, for removing the control of the cut-off relay over the line signal of the called line, thereby permitting the called station to have control of the line signal of the called line.

6. A telephone exchange system including telephone lines extending from sub-stations to an exchange, line signaling apparatus at the exchange for said telephone lines, connecting apparatus at the exchange for uniting lines in conversation, a cut-off relay governed by said connecting apparatus, for preventing the presentation of the line signal of a called line, and electro-magnetic

mechanism, operable by the called party independently of the apparatus of the calling station, for removing the control of the cut-off relay over the line signal of the called line, thereby permitting the called station to have control of the line signal of the called line.

7. A telephone exchange system including telephone lines extending from sub-stations 10 to an exchange, line signaling apparatus at the exchange for said telephone lines, connecting apparatus at the exchange for uniting lines in conversation, a cut-off relay governed by said connecting apparatus, for 15 preventing the presentation of the line signal of a calling line, and means, operable by the calling party independently of the apparatus of the called station, for removing the control of the cut-off relay over the line signal of the calling line, thereby permitting the calling station to have control of the line signal of the calling line.

8. A telephone exchange system including telephone lines extending from sub-stations 25 to an exchange, line signaling apparatus at the exchange for said telephone lines, connecting apparatus at the exchange for uniting lines in conversation, a cut-off relay governed by said connecting apparatus, for 30 preventing the presentation of the line signal of a calling line, and electro-magnetic mechanism, operable by the calling party independently of the apparatus of the called station, for removing the control of the cut-off relay over the line signal of the calling line, thereby permitting the calling station to have control of the line signal of the calling line.

9. A multiple switch-board telephone system including telephonically connected sub-stations and means whereby apparatus of one connected sub-station may dissociate the test system of the switch-board from the line leading to the said sub-station independently 45 of the apparatus at the other sub-station.

10. A multiple switch-board telephone system including telephonically connected sub-stations and means whereby apparatus of one connected sub-station may dissociate the test system of the switch-board from the line leading to said sub-station independently of the apparatus at the other sub-station, said means preventing reassociation of said test system with said line during an 55 established connection.

11. A multiple switch-board telephone system including telephonically connected sub-stations and electro-magnetic means individual to a connecting apparatus, where- 60 by apparatus of one connected sub-station may dissociate the test system of the switch-board from the line leading to said sub-station independently of the apparatus at the other sub-station.

65 12. A multiple switch-board telephone

system including telephonically connected sub-stations and electro-magnetic means individual to a connecting apparatus, whereby apparatus of one connected sub-station may dissociate the test system of the switch-board from the line leading to said sub-station independently of the apparatus at the other sub-station, said means preventing reassociation of said test system with said line during an established connection.

70 13. A multiple switch-board telephone system including telephonically connected sub-stations, a test system, and means operable at one sub-station during an established connection for enabling a line to test idle during an established connection independently of the apparatus at the other sub-station.

75 14. A multiple switch-board telephone system including telephonically connected sub-stations, a test system, and means operable at one substation during connection of line connecting apparatus therewith for enabling a line to test idle during connection of line connecting apparatus therewith independently of the apparatus at the other sub-station.

80 15. A multiple switch-board telephone system including telephonically connected sub-stations, a test system, independent of line circuits, and means operable at one sub-station during an established connection for enabling a line to test idle during an established connection independently of the apparatus at the other substation.

85 16. A multiple switch-board telephone system including telephonically connected sub-stations, a test system, independent of line circuits, and means operable at one sub-station during connection of line connecting apparatus therewith for enabling a line to test idle during connection of line connecting apparatus therewith independently of the apparatus at the other sub-station.

90 17. A multiple switch-board telephone system having telephonically connected sub-stations and a test system independent of line circuits and including means whereby apparatus of one connected sub-station may dissociate the test system of the switch-board from the line leading to said sub-station independently of the apparatus at the other sub-station.

95 18. A multiple switch-board telephone system having telephonically connected sub-stations and a test system independent of line circuits and including means whereby apparatus of one connected sub-station may dissociate the test system of the switch-board from the line leading to said sub-station independently of the apparatus at the other sub-station, said means preventing reassociation of said test system with said line during an established connection.

120 19. A multiple switch-board telephone

system having telephonically connected sub-stations and a test system independent of line circuits and including electro-magnetic means individual to a connecting apparatus, 5 whereby apparatus of one connected sub-station may dissociate the test system of the switch-board from the line leading to said sub-station independently of the apparatus at the other sub-station.

10 20. A multiple switch-board telephone system having telephonically connected sub-stations and a test system independent of line circuits and including electro-magnetic means individual to a connecting apparatus, 15 whereby apparatus of one connected sub-station may dissociate the test system of the switch-board from the line leading to said sub-station, independently of the apparatus at the other sub-station, said means preventing 20 re-association of said test system with said line during an established connection.

21. A telephone exchange system including calling and called telephone lines, the calling line being provided with line equipment at an exchange for initiating connections; a link connector joining said lines and their stations in telephonic connection; means operating by way of the link connector for preventing operation of said line 30 equipment of the calling line; and means within the control of the calling station and operating independently of the called station for breaking the link connector between the aforesaid means and said line equipment to restore said line equipment to the control of the calling station while calling line and link connector contacts are in engagement.

35 22. A telephone exchange system including calling and called telephone lines, the called line being provided with line equipment at an exchange for initiating connections; a link connector joining said lines and their stations in telephonic connection; means operating by way of the link connector for preventing operation of said line equipment of the called line; and means within the control of the called station operating independently of the calling station for breaking the link connector between the aforesaid means and said line equipment to restore said line equipment to the control of the called station while called line and link connector contacts are in engagement.

40 23. A telephone exchange system including calling and called telephone lines, each of said lines being provided with exchange line equipment for initiating connections; a link connector joining said lines and their stations in telephonic connection; means operating 45 by way of the link connector for preventing operation of the line equipment of the calling and called lines; and means at each of the stations operating independently of the other station for breaking the link connector between the aforesaid means and its

line equipment to restore the corresponding line equipment to the control of its station while link connector contacts are in engagement with calling and called line contacts.

5 24. A telephone exchange system including calling and called telephone lines, the calling line being provided with line equipment at an exchange for initiating connections; a link connector joining said lines and their stations in telephonic connection and having operator controlled means for connecting it with the calling line; means operating by way of the link connector for preventing operation of said line equipment of the calling line; and means within the control of the calling station and operating independently of the called station for breaking the link connector between the aforesaid means and said line equipment to restore said line equipment to the control of the calling station while calling line and link connector contacts are in engagement.

75 25. A telephone exchange system including calling and called telephone lines, the called line being provided with line equipment at an exchange for initiating connections; a link connector joining said lines and their stations in telephonic connection and having operator controlled means for connecting it with the called line; means operating by way of the link connector for preventing operation of said line equipment of the called line; and means within the control of the called station operating independently of the calling station for breaking the link connector between the aforesaid means and said line equipment to restore said line equipment to the control of the called station while called line and link connector contacts are in engagement.
